ABSTRACT: Terminal insertion apparatus for inserting boxlike terminals into printed circuit boards has strip feeding means for feeding a continuous strip of end-to-end terminals towards the surface of the board. Leading terminal of strip is severed from the strip at a location above the surface of the board and gripped by an insertion slide which carries the terminal downwardly and inserts it through an opening in the board. Thereafter, legs of this leading terminal, which extend through the board, are bent outwardly to lock the terminal in place. Towards the end of the operating cycle, severing blades, which are movable laterally towards each other and towards the strip of terminals, move inwardly and sever the next adjacent terminal from the strip. This next adjacent terminal is picked up by the inserting means and carried to the board during the next succeeding operating cycle.

TERMINAL INSERTION APPARATUS

BACKGROUND OF THE INVENTION

This invention relates to apparatus for inserting contact terminals into printed circuit boards or the like. The invention is particularly intended for use in the consumer electronics industry, for example, in the manufacture of television sets, where relatively complex printed circuit boards must be produced in large numbers at a very low cost. The production machinery of such boards requires devices for rapidly inserting terminals of the various types needed into the boards as they move past applicators mounted beside the assembly line. A high degree of reliability is required of such applicators for the reason, among others, that the failure of a single applicator requires that an entire production line be shut down with resulting idling of all of the other applicators and other assembly machinery on the production line.

An object of the invention is to provide an improved inserting apparatus for inserting contact terminals into the printed circuit boards. A further object is to provide an apparatus which has an extremely short cycling time and can, therefore, insert an individual terminal into a board during a very short time interval. A further object is to provide a highly reliable apparatus capable of operation for an extended period without substantial servicing or other maintenance. A still further object is to provide an apparatus which is capable of performing a final forming operation on a terminal immediately prior to inserting the terminal into a printed circuit board.

These and other objects of the invention are achieved in a preferred embodiment thereof comprising an apparatus having a strip-feeding means for feeding a continuous strip of end-to-end connected contact terminals towards a printed circuit board. The end portion of the strip is fed to a location immediately above the opening in the board into which a terminal is to be inserted and the leading terminal of the strip is severed from the strip during the final portion of an operating cycle. At the beginning of the next operating cycle, an inserting slide carries the previously severed terminal downwardly, and inserts it through an opening in the printed circuit board. While the leading terminal is being inserted into the board, the strip of terminals is fed a distance equal to the length of a single terminal so that the next adjacent terminal is located at the end of the strip feed path. Thereafter, the insertion slide returns to its starting position and grasps this next adjacent terminal in preparation for the next operating cycle.

In the drawings:

FIG. 1 is a sectional side view of a terminal applicator in accordance with the invention, this view showing the positions of the parts when the insertion slide is in its elevated position at the beginning of the operating cycle and being taken along the lines 1-1 of FIGS. 4 and 5;

FIG. 2 is a view similar to FIG. 1 but showing the positions of the parts at an intermediate stage of an operating cycle and after a terminal has been inserted into a printed circuit board;

FIG. 3 is a view taken along the lines 3-3 of FIG. 1 and again showing the positions of the parts at the beginning of an operating cycle;

FIG. 3A is a view similar to FIG. 3 but showing the positions of the parts at the intermediate stage of FIG. 2;

FIG. 3B is a fragmentary view showing details of the strip feed slide;

FIGS. 4 and 5 are views taken along the lines 4-4 of FIG. 2 and 5-5 of FIG. 1 respectively;

FIG. 6 is a fragmentary view on an enlarged scale taken along the lines 6-6 of FIG. 1 and showing the relationships of the severing blades and the insertion slide to each other at the beginning of the operating cycle;

FIGS. 7 and 8 are views similar to FIG. 6 but showing the positions of the parts at successive stages of the operating cycle;

FIG. 9 is a view taken along the lines 9-9 of FIG. 6;

FIG. 10 is a view similar to FIG. 9 but showing the positions of the parts after insertion of the terminal into the printed circuit board;

FIG. 11 is a fragmentary perspective view showing the end portion of the insertion slide with the parts exploded from each other in the interest of clarity;

FIG. 12 is a fragmentary perspective view showing the lower portions of the insertion slide and associated structure; and

FIG. 13 is a descriptive timing diagram showing the relative movements of the parts during a complete operating cycle.

Referring first to FIGS. 6 and 10, the disclosed embodiment of the invention is adapted to insert terminals 202 which are manufactured in the form of end-to-end terminal strip 200, each terminal being axially aligned with the next adjacent terminal of the strip and integral therewith. The individual terminals comprise a pair of spaced apart generally rectangular boxlike section 204, 206 which are connected to each other on two opposite sides by integral straps 208, 210. Contact springs 212, are integral with the lower box section 206 and extend diagonally, with respect to the axis of the terminal, towards each other. A pair of legs 214, 216 extend downwardly as viewed in the drawings from the lower box section and are adapted to be inserted through the opening in the printed circuit board. After such insertion, these legs are bent outwardly to hold the terminal in place until it is soldered to the board. After the terminal has been secured to the board, it is adapted to receive a blade contact having a rectangular cross section which is inserted between the springs 212 to establish electrical contacts therewith. Terminals of the particular type as shown in FIGS. 6-10 are more fully described in U.S. Pat. No. 3,270,251. It will be understood that the principles of the invention can be adapted to the insertion of terminals other than the specific terminal shown in the drawing.

Referring now to FIGS. 1-5, an applicator 2 in accordance with the invention is adapted to be mounted on the end of an arm 4 of a suitable frame above the surface of the printed circuit board 6. It will be understood that the board 6 will normally be mounted on a suitable conveyor and that during each operating cycle, a single terminal will be inserted into the board and the conveyor will then be indexed to position another printed circuit board under the applicator. The frame on which the applicator is mounted may be a conventional C-type press frame as disclosed, for example, in U.S. Pat. application Ser. No. 717,086, filed Mar. 29, 1968, by Willard L. Busler et al.

The applicator 2 comprises a generally L-shaped frame casting 8 (FIG. 5) secured to the end of the arm 4 and having sides 10, 12. Arm 10 has an upwardly projecting extension 11, shown fragmentarily in FIGS. 1 and 2, on which an air cylinder, referred to below, is mounted. An L-shaped bracket 14 is mounted on one side of the arm 12 and a gib 18 is mounted on this bracket. A complementary gib 16 is mounted on the arm 10, these gibs functioning as guides for a generally channel-shaped main drive slide 20 which reciprocates vertically during the operating cycle. The main drive slide has a web portion 22 and a pair of opposed arms or sidewalls 24, 26, the outer surface of which are grooved to receive the gibs.

The main drive slide 20 is moved downwardly then upwardly during an operating cycle by means of a piston rod 28 extending from a suitable piston-cylinder (not shown) having a clevis 30 threaded to its end. The clevis 30 has a slot 29 on its rightwardly facing side as viewed in FIG. 1. A plate 32 is received in this slot and supported by an arm 31 on the lower end of the clevis. Plate 32 extends across the upper ends of, and is secured to, the arms or sides 24, 26 of the main drive slide by fasteners 34 (FIG. 4).

An insertion drive slide 36 is slidably mounted between the arms 24, 26 of the main drive slide and has a rightwardly facing groove 38 (as viewed in FIG. 5) extending centrally along its exposed side. An insertion slide assembly 40 (FIG. 1), having a rectangular cross section is mounted in this groove and carries, on its lower end, the gripping means for gripping the terminal being inserted into the printed circuit board as will be described subsequently. This insertion slide assembly 40 is keyed to the insertion drive slide 36 in a manner described below. Insertion slide 36 is normally biased upwardly as viewed in the drawing by means of a pair of coil springs 42

which extend through holes in the insertion slide. The upper ends of these springs are connected to pins 44 in the plate 32 (FIG. 4) and the lower ends of the springs are connected to pins 46 mounted in the lower end of the insertion drive slide. Upward movement of the insertion drive slide beyond the position shown in FIG. 1 is prevented by means of a rod 48 which extends through an opening in the plate 32 and is secured in an opening in the insertion slide 36 by a setscrew 41, see FIG. 4. The upper end of this rod 48 is adapted to bear against the end of a setscrew 50 mounted in a fixed bracket 52 secured to the extension 11 of the frame wall 10.

The insertion slide 40 is yieldably coupled to the insertion drive slide 36 by means of a spool 54 which is contained in an opening 68 in the lower end in the lower portion of the insertion drive slide 36. Spool 54 has a circumferential recess 56 intermediate its ends which receives a laterally extending boss 58 on the lower end portion of the insertion slide assembly 40. The spool 40 is slidably mounted on a rod 60 which is threaded at 64 into the lower end 62 of the insertion drive slide and which extends upwardly through opening 68 and into a drilled hole 66 in the insertion drive slide at the upper end of the opening 68. A coil spring 70 surrounds the rod 60 and bears against the upper surface of spool 54 and against the insertion drive slide 36 at the upper end of opening 68. As explained immediately below, this coupling arrangement permits overtravel of insertion drive slide 36 with respect to insertion slide assembly 40 and thereby protects the printed circuit board into which terminals are being driven against damage.

It will be apparent from FIG. 1 that the spool 54 is spring loaded downwardly by the spring 70 and that downward thrust is transmitted from the insertion drive slide 36 through the spring 70 and spool 54 to the boss 58 on the insertion slide 40. It should be mentioned that the spring 70 is relatively a stiff spring and will be compressed only if a substantial resistance is presented to the spool 54 during downward movement thereof. By virtue of this arrangement, if the insertion slide assembly 40 reaches the lower limit of its travel and fully inserts the terminal through a printed circuit board before the insertion drive slide 36 has reached the lower limit of its travel, the insertion slide assembly will cease to move downwardly and there will be a slight compression of the spring 70 with concomitant downward movement of the insertion drive slide relative to the spool 54. This arrangement prevents damage to the printed circuit board or the terminal if the terminal should be fully inserted before the end of the downward stroke of the drive slide and thereby permits the applicator to be used on printed circuit boards of varying thicknesses.

A cylindrical rod 74 is pinned or otherwise secured in the laterally extending ear 72 on the insertion slide 40. This rod, 74, extends downwardly through a drilled opening 76 in a plate member 78 secured intermediate the ends of a generally channel-shaped frame piece 80, which, in turn, is secured to the wall 10 of the casting by fastening means. The terminal strip 200 is fed downwardly through the plate number 78 through a slot 84 therein and towards the lower end of the insertion slide 40 as will be described below.

The insertion slide 40 has an extension 86 on its lower end, which projects diagonally towards the feed path of the terminal strip, and a depending arm portion 88 which extends parallel to the feed path. The rod 74, has a generally H-shaped block 90 on its lower end (FIG. 12) having a recess 92 on its left-hand side as viewed in the drawing. This recess accommodates the lower portion of the insertion slide member 40 and the extension 86 thereon. The recess 94 on the opposite side of the block 90 receives an extension 96 of the plate member 78 and has a latch block 100 mounted therein. A latch arm 98 is pivotally secured at 102 in a recess in the block 100 and a spring 104 interposed between the block and the latch arm normally biases the lower end portion 101 of this latch arm towards the arm portion 88 of the extension 86 of the insertion slide. A set screw 106 is mounted in the upper end of the block 100 to control the movement of the lower end of the latch arm 98 so that it will effectively grip the lead-

ing terminal of the strip during insertion as will be described below. The plate member 78 is cut away on its lower side as shown at 108 to accommodate the right hand portion of the block 90 and the latching block structure 100 as shown best in FIG. 1. The right hand surface of the block 100 bear against a bearing surface of a plate 110 secured to the frame extension 80 and guides the lower end of the insertion slide and the terminal gripping means mounted thereon along a straight line path towards and away from the printed circuit board.

10 Turning now to FIGS. 6—11, the rightwardly facing surface 116 of the end portion 88 of the insertion slide member 40 has a pair of spaced-apart rightwardly extending flanges 118 which are adapted to grip the leading terminal of the strip as shown in FIG. 6. Immediately above these flanges, a pair of spaced-apart bosses 120 are provided which have surfaces sloping inwardly towards the feed path and towards each other thereby to guide the strip downwardly as viewed in FIG. 6 during the feeding operation. The end portion 122 of the latch arm 98 has a leftwardly extending boss 124 which lodges between the box portions of the leading terminal and serves to hold this terminal in position when the insertion slide moves relatively towards the printed circuit board.

15 During the final portion of the operating cycle, the leading 25 terminal of the continuous terminal strip is severed from the strip by means of a pair of severing blades 126, 128 which are slidably mounted in channels 130 in blocks 132. The guide blocks 132 are secured to the surface of the lower end of the frame member 80 by fasteners 133 so that they remain stationary during downward movement of the insertion assembly. Each blade 126, 128 is provided with a pin 138 intermediate its ends which receives the notched lower ends of a pair of spaced-apart levers 140 mounted on opposite sides of the strip feed path. These levers are pivoted intermediate their ends at 30 142 in blocks 144 which are also secured to the frame member 80. The upper ends 146 of the levers are provided with cam followers 148 which extend into cam slots 150 in plates 152. The plates 152 are mounted on the arms 24, 26 of the main power slide 20 so that they move upwardly and downwardly 35 relative to the cam followers 148 during the operating cycle. The contours of the slots 150 are such that the severing blades are in their closed condition at the beginning of the operating cycle and dwell in their closed condition during the initial stages of downward movement of the main drive slide 20. The 40 blades move relatively apart as shown in the timing diagram and dwell in their open position (FIG. 3A) while the inserting operation is being carried out and during a portion of the return stroke of the main drive slide. The blades are closed during the final portion of the upward stroke of the drive slide and sever the previously fed terminal from the strip so that it can be picked up and carried downwardly during the succeeding operating cycle by the insertion slide assembly. It should be mentioned that the blocks 144 on which the levers 140 are 45 mounted are advantageously adjustable by means of adjusting screws 154 in order to precisely sever and form the terminal.

50 The terminal strip is fed a distance equal to the length of a single terminal while the inserting operation is being carried out by means of a strip feed pawl 160 pivotally mounted at 60 162 in a recess 166 of a strip feed slide 168. The strip feed slide, in turn, is slidably mounted in a recess 170 in a block 172 which is secured against one side of the plate 78 by fasteners 171 (FIG. 1 and 5). The end portion of the feed pawl extends through an opening 164 in the plate member 78 and 65 engages the forth terminal from the end of the strip immediately adjacent to its forward box section. A spring 169 mounted on the feed slide biases the feed pawl into engagement with the strip. Feed slide 168 is normally biased upwardly by a spring 178 contained in a drilled opening in the 70 feed slide. This spring bears at its lower end against a pin 174 fixed in the block 172 and at its upper end against a cap member 180 which closes the opening in which the spring is contained. The pin 174 extends through aligned slots 175 in the feed slide and is, therefore, fixed with respect to the slide. 75 Feeding is accomplished by means of a set screw 179 mounted

on the clevis 30. Upon downward movement of the main power slide 20, this set screw engages an ear 181 which extends from the feed slide and drives the slide through its feeding stroke, the return of the feed slide being effected by the spring 178.

It is desirable to be able to feed the terminal strip through a single feeding stroke manually while the applicator is being adjusted or serviced. Manual feeding of the strip in the disclosed embodiment can be effected by a plunger 183 which is slidably mounted in an externally threaded bushing 184. This bushing, in turn, is mounted in a bracket 186 secured to the side of the plate 78 above the block 172. The plunger is merely pressed down until it engages the cap piece 80 in order to feed the strip.

During retraction of the feed slide and during movement of the feed pawl 160 over the strip, retractile movement of the strip is prevented by means of a stop pawl 188 mounted in an opening in a block 192 on the opposite side of the plate 78 from the side on which the feed mechanism is mounted. The end portion of this stop pawl extends through an opening 190 in the wall of the plate member 78 to permit the pawl to engage the strip. The pawl is normally biased into engagement with the strip by means of a spring as shown in FIG. 3, an arrangement which permits downward movement of the strip during downward movement of the feed slide but prevents upward movement of the strip during the return of the feed slide.

When a new strip of terminals is being inserted through the passageway 84, or when the strip of terminals is being removed from this passageway, it is desirable to disengage the feed pawl 160 and the stop pawl 188 from the strip. In the disclosed embodiment, this is accomplished by a cam 185 contained in a recess 191 in the plate 78. Cam 185 is secured to the end of a shaft 187 that extends beyond the surface of the plate 78 and has a knob 189 on its end so that the cam can be rotated from its normal position. Upon such rotation of the cam, it engages pins 193, 195 in the stop pawl and feed pawl and moves these members away from the strip so that the strip can be inserted or withdrawn from the strip feed passageway.

After the insertion of a terminal through an opening in the printed circuit board, the legs 214, 216 of the terminal are bent outwardly by a pair of normally closed spreading fingers 194. These fingers are disposed beneath, and in alignment with, the opening in the printed circuit board so that when the terminal is inserted, the legs will be on the opposite sides of the fingers. The fingers are then moved apart to bend the legs laterally as shown in FIG. 8 and secure the terminal temporarily to the board until it is soldered. The mechanism for spreading these fingers may be, for example, of the type shown in U.S. Pat. No. 3,293,735 or of any other desired type. It is only necessary that these fingers move apart after the insertion operation has been completed.

A suitable drag mechanism is provided on the strip in the form of a block 195 mounted in a suitable recess in the plate 78 and biased towards the strip by springs 196. This clamping block or drag block can be moved away from the strip thereby to permit removal of the strip or insertion of a new strip into the applicator by means of a cam lever 197 pivotally mounted on a control rod 198 which is secured as shown in FIG. 1 to the clamping block.

The operation of the disclosed embodiment is best described with reference to the timing diagram, FIG. 13. During each operating cycle, the main drive slide 20 is driven downwardly and is then retracted by the piston rod 28. This piston rod may be controlled by any suitable valve system (not specifically shown) which is advantageously arranged to respond to movement of the conveyor on which the printed circuit boards are carried past the inserting apparatus. The insertion slide 36 dwells in its upper position during an initial portion of the cycle and is moved downwardly with the main drive slide 20 after the lower surface of the clevis 30 on the main drive slide moves against the upper end of the insertion slide 36. The insertion slide and the main drive slide move downwardly as a unit until the terminal held in the tip 88 of

the insertion slide has been inserted into the board and staked thereto by spreading of the staking members 194. During the upward stroke of the main drive slide 20, the insertion slide moves with the main drive slide until the stop pin 48 on the upper end of the insertion slide engages the fixed stop screw 50. The terminal severing blades 126, 128 are in their closed positions at the beginning of the operating cycle and are opened during downward movement of the main drive slide by the levers 140 and cams 150. These blades dwell in their opened positions while the terminal inserting operation is carried out and while the terminal strip is fed to locate the leading terminal of the strip immediately beneath the severing blades. The severing blades are closed towards the end of the operating cycle, i.e., during the final portion of the upward stroke of the main drive slide, to sever the leading terminal of the strip and they dwell in their closed positions during the final portion of the cycle. The strip feed pawl 160 is in its retracted position (FIG. 3) at the beginning of the cycle and dwells in this position until the feed slide 168 is engaged by the setscrew 79 mounted on the clevis 30 of the main drive slide. Feed pawl 160 is then moved downwardly during the final portion of the downward stroke of the main drive slide to feed the strip and is retracted immediately thereafter as the main drive slide moves upwardly from its lowermost position. As indicated in the timing diagram, feeding of the terminal strip is completed well before the leading terminal of the fed strip is severed by the severing blades 126, 128. After this leading terminal has been severed from the strip, it is held in the lower end of the insertion slide in preparation for the next operating cycle.

Changes in construction will occur to those skilled in the art and various apparently different modifications and embodiments may be made without departing from the scope of the invention. The matter set forth in the foregoing description and accompanying drawings is offered by way of illustration only.

I claim:

1. Apparatus for inserting contact terminals into a printed circuit board or the like, said terminals being in end-to-end strip form, said apparatus comprising:
 strip-feeding means for feeding said strip along a predetermined feed path, said feed path terminating at a location above a printed circuit board;
 insertion slide means movable from said location towards and away from said printed circuit board, said insertion slide means having terminal-gripping means for carrying the leading terminal of said strip towards said printed circuit board;
 a pair of cooperable severing members disposed on opposite sides of said feed path at said location, said severing members being movable relatively towards each other, to shear said leading terminal from said strip, and then relatively away from each other to permit feeding of said strip; and
 actuating means effective to move said severing blades towards each other during retractile movement of said insertion means during the end portion of one operating cycle and for moving said severing members away from each other and for moving said insertion means towards said printed circuit board during the next operating cycle.

2. Apparatus as set forth in claim 1 wherein said terminal gripping means comprises a pair of arms on said insertion slide means, one of said arms being resiliently biased towards the other arm whereby said leading terminal is resiliently gripped between said arms.

3. Apparatus as set forth in claim 1 wherein said actuating means comprises a reciprocable drive slide, said drive slide having a lost motion coupling to said insertion slide means whereby movement of said insertion slide means towards said printed circuit board commences after movement of said drive slide, and camming means effective between said drive slide and said severing blades to move said severing blades away from said strip prior to movement of said insertion slide means.

4. Apparatus as set forth in claim 3 wherein said insertion slide means comprises an insertion drive slide and an insertion slide, said lost motion coupling being between said main drive slide and said insertion drive slide.

5. Apparatus as set forth in claim 4 including a stiffly yieldable coupling between said insertion drive slide and said inser-

tion slide, said insertion drive slide being movable relative to said insertion slide in the event of complete insertion of said leading terminal through said board prior to the end of the stroke of said insertion drive slide.
